RAILWAY TRAFFIC CONTROLLING
APPARATUS

Ralph R. Kemmerer, Swissvale, and Charles W. Failor, Forest Hills, Pa., assignors to The Union Switch & Signal Company, Swissvale, Pa., a corporation of Pennsylvania

Application April 19, 1939, Serial No. 268,788

16 Claims. (Cl. 246—130)

Our invention relates to railway traffic controlling apparatus and it has special reference to the organization of such apparatus into signaling systems of the class wherein coded trackway energy is utilized to control either or both wayside signals and train carried cab signals.

One object of our invention is to provide a new and improved form of such organization which protects against the giving of false "proceed" indications in the event of breakdown of the insulated joints which electrically separate the rails of adjacent track sections.

Another object is to apply this protection to signaling systems which use code following track 15 relays of the single element type.

An additional object is to effect the named protection without requiring that devices at opposite ends of the automatic signal block be interconnected by line wires.

20 A further object is to extend the broken-down joint protection to all highway crossing signals which are within the limits of each of the blocks of the automatic wayside system.

A still further object is to accomplish the 25 above without dispensing with any of the desirable features of continuously coded track circuit control.

In practicing our invention we attain the above and other objects and advantages by: staggering 30 the polarities of adjacent track circuits; supplementing each of the code following track relays of the automatic block system by an auxiliary track relay which responds only to rail energy of "normal" polarity; and arranging that each release 35 of this auxiliary relay will cause the associated wayside and/or highway crossing signal to display a restrictive warning. Should, now, the coded energy from one track section leak forwardly over a defective joint into the rails of an adjacent section, this auxiliary relay immediately releases and causes the associated signal to indicate the faulty condition by a display of the above 40 mentioned restrictive aspect.

We shall describe a few forms of railway traffic 45 controlling apparatus embodying our invention, and shall then point out the novel features thereof in claims. These illustrative embodiments are disclosed in the accompanying drawings in which:

50 Figs. 1a and 1b when placed end to end in the order named constitute a diagrammatic representation of a stretch of railway track which is equipped with traffic controlling apparatus embodying our invention;

55 Fig. 2 is a showing of filter-rectifier connec-

tions which are suitable for inclusion in the track relay supply circuits of Fig. 1;

Fig. 3 is a partial representation of the highway crossing control circuits of Fig. 1a supplemented to provide for two direction running, as 5 in Fig. 1b;

Fig. 4 is a partial reproduction of one of the location equipments of Fig. 1 showing the track and auxiliary relays thereof connected in parallel instead of in series; and 10

Fig. 5 is a similar representation of corresponding apparatus modified to include a slow release auxiliary relay of the non-centrifugal type.

In the several views of the drawings like reference characters designate corresponding parts. 15 Referring first to the composite diagram of Figs. 1a—b, the improvements of our invention are there disclosed as being incorporated in the trackway portion of a combined automatic block signaling and cab signaling system for a track 20 1—2 over which it will be assumed that traffic moves in the single direction indicated by the arrows, or from left to right in the diagram. Insulated rail joints 3 divide the protected stretch of this track into the customary successive sections and the rails of each of these sections form 25 a part of a track circuit of the usual character.

The particular track stretch which is represented in Figs. 1a—b is intended for use in a railway system employing electric propulsion and 30 for this reason alternating current track circuit energy is used together with impedance bonds 4 of the customary form which conduct propulsion current around each pair of the insulated rail joints. As the description proceeds, however, it 35 will become apparent that the apparatus of our invention is equally well suited for use on a steam road, in which application either direct current or alternating current track circuit energy may be used; in such an application, moreover, the 40 bonds 4 would, of course, be omitted.

In the composite diagram of Figs. 1a—b only a single signal block D—E of the referred to 45 automatic signaling system is completely shown. This particular block embraces two cut locations D_a and D_b which are respectively occasioned by intersecting highways 6 and 7 and with which highway crossing protective signals XS are associated in the usual manner. Because of these two cuts the main signal block D—E comprises 50 three consecutive sections of track D—D_a, D_a—D_b and D_b—E.

Positioned at the entrance of each of the main signal blocks (locations D, E, etc.) of the referred to automatic system is a wayside signal S, 55

illustratively shown as being of the color light type, which is adapted to indicate to an approaching train the nature of the traffic conditions in the blocks immediately ahead. As signal S_d protects the entire block D—E, no wayside signal is provided at either of the cut section locations Da or Db .

The rails of each of the referred to sections of track form a part of a track circuit to which coded alternating current train control energy normally is supplied through a track transformer TT connected with the rails at the traffic leaving or exit end of the section by means of a circuit which includes the usual current limiting reactor 8. This energy is derived from any suitable alternating current source and distributed to the several locations of track section division in conventional manner, as by the aid of a transmission circuit (not shown) extending along the right-of-way. In the diagram, characters B and C designate power distribution terminals which are supplied from one such source; to facilitate explanation, it will be assumed that the energy of this source has a frequency of 100 cycles per second.

The particular signaling system shown in Fig. 1 is of the three indication variety and it makes use of track circuit energy of two different codings. These codings are produced by a code transmitter CT which interrupts the supply circuit of the associated track transformer TT a definite number of times per minute according to the traffic or other conditions ahead. In the illustrative form shown, each device CT is provided with two circuit making and breaking contacts 80 and 180 which are continuously actuated by a motor or other suitable mechanism (not shown in detail) at two different speeds. For purposes of explanation, it will be assumed that these speeds are such as respectively to provide codes of 80 and 180 energy pulses per minute.

Each of the referred to track circuits further includes the operating winding of a track relay TR which is installed at the traffic entering end of each track section and which receives operating energy from the rails thereof. Each of these track relays is of the single element code following type and may be designed to respond either to direct or to alternating current. When the relay is of the alternating current design, the winding thereof is directly connected to the rails of the associated track section in the manner represented at location E in Fig. 1b; when, however, the relay is of the direct current design, this connection includes the resonant transformer unit shown at 9 at each of the diagram locations D, Da and Db . Typically, this unit 9 will include a transformer, a capacitor, a reactor and a rectifier connected as shown in Fig. 2 and so proportioned as freely to pass the 100 cycle coded signal control energy which is received from the trackway and to rectify this energy before applying it to the relay winding.

In the illustrative automatic block signaling system of Figs. 1a—b, energy of one or the other of the previously described 80 and 180 codings is normally fed to the track circuits at all times and this coded energy is used to control both the wayside signals and cab signals mounted on a train which proceeds along the track 1—2. Because of the well-known character of such cab signals, no attempt has been made to disclose them in the present application.

The aspect that is displayed by the wayside signal S at the entrance of each of the main

signal blocks is determined by a pair of decoding relays DRH and DR180 installed at each signal location in conventional manner. Relay DR180 is a code distinguishing device while relay DRH functions to detect the presence or absence of code following operation by track relay TR. In addition to controlling the associated wayside signal, each of the code detecting relays DRH also selects the coding of the energy which is supplied to the rails of the track section to the rear of the signal.

In the illustrative arrangement which we have shown, both of the decoding relays DRH and DR180 receive their energizing current from the secondary winding of a decoding transformer DT. This transformer is represented as being of conventional design and as having a primary energizing circuit that is pole changed in customary manner by a contact 12 of the code following track relay TR. Each time that this contact is picked up, direct current flows in one direction through one portion of the transformer primary (by way of a circuit which extends from the positive terminal of a suitable supply source through front contact 12, conductor 14, the right half of the transformer winding and mid tap 15 back to the negative terminal of the supply source) and each time that contact 12 is released, the current flows in the opposite direction through another portion of the winding (by way of a circuit which includes conductor 16 and the left winding half).

The resulting alternating current voltage of code pulse frequency which is induced in the secondary winding of transformer DT supplies the winding of code detecting relay DRH with current of pick-up intensity whenever the associated track relay TR follows either of the 80 or 180 trackway codes. Included in the supply circuit of this relay is a rectifier unit DU80 which permits current passage at either of the code pulse frequencies named, and thus renders the relay responsive to both of the two codes.

In consequence, this code detecting relay DRH picks up whenever the associated track relay TR follows either of the 80 or 180 trackway codes. The code distinguishing relay DR180, however, is arranged to pick up only when the received code is of the 180 energy pulse per minute variety and for effecting this selective response the energizing circuit for relay DR180 includes a tuned unit DU180 which passes current of pick-up intensity to the winding of that relay only when the frequency of the decoding transformer output voltage is of the 180 code rate. Because of the well-known character of such tuned units, no detailed description thereof is here given.

The aspect displayed by the associated wayside signal S is determined by a contact 13 of the code detecting relay DRH acting in cooperation with a contact 19 of the code distinguishing relay DR180. In the event that the track relay TR fails to respond to coded energy from the trackway, the contacts of both decoding relays will remain released and under this condition (which is in effect when the guarded track section is occupied by a train) the controlled wayside signal S displays the indication of "stop" by virtue of lamp R thereof receiving lighting current over a circuit extending from the positive terminal of a suitable supply source through back contact 18 of relay DRH, conductor 21 and the lamp R back to the negative terminal of the supply source.

When, however, energy of the low speed or 80

pulse per minute coding is received and responded to by the track relay TR, code detecting relay DRH picks up and under this condition the controlled wayside signal S displays the "approach" 5 indication by virtue of lamp Y thereof receiving lighting current over a circuit that extends from the positive supply terminal through front contact 18 of relay DRH, back contact 19 of relay DR180, conductor 22 and the lamp Y back 10 to the negative supply terminal. Finally, when energy of the 180 pulse per minute coding is received from the trackway, both of the relays DRH and DR180 pick up their contacts and the controlled wayside signal S then displays the 15 "clear" indication by virtue of lamp G thereof receiving lighting current over a circuit which may be traced from the positive supply terminal through front contact 18 of relay DRH, front contact 19 of relay DR180, conductor 23 and the 20 lamp G back to the negative supply terminal.

In selecting the coding of the energy which is supplied to the rails of the track section to the rear of each of the wayside signals, the code detecting relay at each of the locations D, E, etc. 25 makes use of a contact 24 which is included in the supply circuit for the section to the rear of that location. Depending upon whether this contact is picked up or released, the primary winding of the associated track transformer TT 30 is periodically connected with the alternating current source B-C over one or the other of coding contacts 180 and 80 of device CT.

The former condition is in effect when a train occupies the advance section of track and releases both the track relay TR and the code detecting relay DRH at the entrance end thereof; under that former condition the rails of the rear 35 track section receive energy of the 80 pulse per minute coding over a circuit which may be traced from the supply terminal B through the coding contact 80 of device CT, conductor 25, back contact 24 of relay DRH, conductor 26 and the primary of the track transformer TT 40 back to the supply terminal C.

The latter condition is in effect when energy of either the 80 or the 180 pulse per minute coding is received and responded to by the track relay TR; in that event the code detecting relay DRH is held continuously picked up and the 45 rails of the rear track section then receive energy of the 180 pulse per minute coding over a circuit which may be traced from the supply terminal B through the coding contact 180 of device CT, conductor 27, front contact 24 of relay DRH, conductor 26 and the primary of track 50 transformer TT back to supply terminal C.

From the foregoing it will be seen that the illustrative organization of apparatus which is included in the composite diagram of Figs. 1a-5 55 constitutes the trackway portions of a three indication combined automatic block signaling and cab signaling system which operates in conventional manner.

As will be explained more in detail presently, the equipment at each of the two cut section locations Da and Db is arranged to repeat into the rails of the section to the rear of the locations the pulses of coded energy which are received from the rails of the section ahead of the location and in this manner the pulses of coded energy which are supplied through the rearwardly extending rails at the exit end E of the main signal block D-E are transmitted around the insulated joints 3 at each of the two cut section locations and thence over the rails ahead of the 60

entrance end D of the signal block to the track relay TR at that entrance location. The just referred to conventional operation of the automatic block signaling system herein disclosed applies, therefore, when the system is used with signal blocks which both do and do not contain cut sections. 5

The illustrative organization of the represented coded system of automatic block signaling having been described, attention will now be directed to 10 the herein disclosed facilities for protecting against the giving of false "proceed" indications in the event of breakdown of the insulated joints 3 which electrically separate the rails of adjacent 15 sections of the signaled stretch of track.

Such a joint failure is hazardous in that its usual effect is to cause the wayside signal S at the location of the fault to give a "proceed" indication even though a train may occupy the track block which the signal guards. Assume, for example, that the joints 3 at location D break down upon the passage of a train through the block D-E of the diagram of Figs. 1a-b. This permits energy of the 80 coding to feed over the 20 faulty joints from the rear section rails into the 25 rails of the occupied forward section and as soon as the rear of the train passes some distance beyond the point of connection of the winding of track relay TR with the rails of this forward section, the potential between these rails (resulting 30 from the rear section leakage energy) rises to a point sufficient to effect code following operation on the part of relay TR. Acting in the normal manner through the associated decoding relays DRH and DR180, this causes the control wayside 35 signal Sd to display the yellow or "approach" indication.

Were the leakage energy allowed, as in the past, to persist in influencing the decoding apparatus, it would transfer the feed circuit for transformer 40 TT from the 80 coding contact to the 180 coding contact and that, in turn, would cause the energization of relay DR180. This would cause the display of a "clear" or green aspect by signal Sd 45 and thereby falsely advise the engineman of a following train that the block D-E is vacant when in reality it is occupied.

In the case of steam territory where the track rails 1 and 2 do not form part of a propulsion circuit through which driving energy is supplied 50 to electric locomotives, the conditions just stated result only in the event that both of the insulated joints 3 at the signal location are defective simultaneously and thus interconnect rail 1 of the rear section with rail 1 of the forward section and rail 55 2 of the rear section with rail 2 of the forward section. In electrified territory, however, a single broken-down insulated joint 3 is the full equivalent of the just described two broken-down joints in steam road territory. 60

This is because of the auto-transformer action of the impedance bonds 4. Should, for example, the joint in rail 1 become defective and establish direct conduction from the rear section length to the forward section length of that rail, there is 65 completed by the impedance bonds 4 a return path around the companion joint in rail 2 and this produces the same effect as were this second joint also to lose its insulating quality. In electrified territory, therefore, the probability of the 70 false "proceed" signal indication previously discussed is comparatively high and requires special protection facilities to prevent accidents and damage in the event of a broken-down rail joint.

In the improved form of organization of our 75

invention, this protection is effected at each signal location by staggering the polarities of adjacent track circuits, supplementing each of the code following track relays of the automatic block system by an auxiliary track relay CTR which responds only to rail energy of normal polarity, and arranging that each release of this auxiliary relay will cause the associated signal to display a restrictive warning.

The staggering of the polarities of adjacent track circuits may, of course, be effected in any suitable manner. Conveniently, this result may be achieved by interposing the leads that connect the track transformer TT with the rails 1 and 2 at the exit end of the consecutive sections of track. In the particular arrangement shown, transformer TT at the exit of section D—Da is so connected with the rails of that section that the right terminal of the transformer secondary is joined with rail 1 and the left terminal with rail 2; the transformer connection is reversed at the exit of section Da—Db so that there the right terminal of the transformer secondary is joined with rail 2 and the left terminal with rail 1; the connection is made in the first named manner at the exit end of section Db—E so that there the right terminal of the transformer secondary is joined with rail 1 and the left terminal with rail 2; and so on. Assuming that at a given instant the polarity of the right terminal is positive, the relative polarities of the rails of the several consecutive track sections will at that instant be as marked by the plus and minus signs in the composite diagram of Figs. 1a—b. That is, in section D—Da rail 1 will be positive and rail 2 negative, in section Da—Db rail 1 will be negative and rail 2 positive, in section Db—E rail 1 will be positive and rail 2 negative, and so on.

The auxiliary track relay CTR which supplements each of the code following track relays TR of the signaling system is connected to receive rail energy simultaneously with the device TR and may be of any suitable design which responds only to a received energy which has a polarity that is "normal" for the particular track circuit and which is sufficiently slow in releasing as to bridge the spacing between consecutive pulses of this received energy when it is coded at any of the several rates of modulation that the signaling system employs.

As shown at each of the four locations in the composite diagram of Figs. 1a—b, each of these auxiliary track relays is of the centrifugal frequency selective type. It is provided with a control winding 29 which receives trackway energy over a serial connection with the supply circuit for the code following device TR and also has a second or local winding 30 which is arranged to receive energization from the alternating current source B—C over front contact 11 of the signaling system relay TR. These two windings 29 and 30 form a part of an induction motor which operates the relay contacts by rotating a fly ball mechanism 31. As long as this mechanism is at rest the contacts occupy their downward or released positions; when, however, the device is rotated in a normal or forward direction the fly balls are moved outwardly by centrifugal action and this movement is utilized to raise the relay contacts.

To prevent the relay from responding to rail potential having an instantaneous polarity which is opposite to that of the current which the control winding 29 normally receives from the track

rails, each of the auxiliary relays CTR is provided with means (not shown) which make it unresponsive to reverse energization of any degree. Conveniently, such means may take the form of a ratchet device (not illustrated) associated with the mechanism 31 and arranged to permit the fly balls of that mechanism to be rotated only in the normal or forward (and not in the reverse) direction.

The contacts of each of the devices CTR reach their fully actuated or picked-up positions only when the speed of this rotation is of the high value which results when the relay windings are energized from the 100 cycle supply circuit B—C. As any energy of the conventional 25 cycle electric propulsion frequency which may accidentally enter the relay (as under unbalanced track circuit conditions) is incapable of producing the critical speed above referred to, false contact closure in electrified territory applications due to stray propulsion current thus becomes impossible.

As the description proceeds it will be apparent that instead of connecting the control winding 29 in series with the supply circuit for the code following track relay TR, this control winding 29 of the auxiliary relay CTR may also be connected in parallel with the named supply circuit. Such a parallel connection is shown in Fig. 4 and will be further discussed at a later point in this specification. Likewise, it will also become apparent that the auxiliary device need not in all cases be of the centrifugal frequency selective type which is illustrated in Figs. 1 and 4 but may be of any suitable design which gives a polarized form of response and is sufficiently slow in releasing as to bridge the spacing between consecutive pulses of the coded signal control energy which is received from the trackway. A second form of auxiliary relay having this characteristic is represented at CTRa, Fig. 5, and it also will be further described later.

Each of the auxiliary track relays CTR is so arranged that each release of its contacts will cause the associated wayside and/or highway crossing signal to display a restrictive warning. At each of the wayside signal locations D, E, etc. this arrangement takes the form of a contact 33 which is included in the primary exciting circuit for the decoding transformer DT at that location. As long as contact 33 occupies the represented picked-up position, this circuit is connected with the positive supply circuit over a front point of the contact; the code following track relay TR then causes the two decoding relays DRH and DR180 to control the wayside signal S in normal manner. When, however, the auxiliary relay CTR becomes released, this contact 33 opens the decoding transformer exciting circuit and thus causes both of the decoding relays DRH and DR180 to go to the released positions regardless of whether the code following track relay TR may be responding to one or another of the 80 and 180 pulse per minute trackway codes. Under the condition just stated, the controlled wayside signal S displays the "stop" indication by virtue of contact 18 of relay DRH completing the lighting circuit for the red lamp R.

From the foregoing it will be seen that as long as there is no failure of an insulated rail joint 3 the auxiliary or protective relay CTR does not alter the normal operation of the coded system of automatic block signaling. Each of the code following track relays TR responds to the received trackway energy in the same manner as were

the control winding 29 of the auxiliary device not to be included in the supply circuit for the relay TR. That is, each pulse of coded energy which is transmitted over the rails to the entrance end of the track section energizes both of the relays TR and CTR over a circuit which may be traced from the positive polarity rail (rail 1 in the case of each of sections D—Da and Db—E and rail 2 in the case of section Da—Db) through conductor 34, the control winding 29 of relay CTR, conductor 35, the winding of relay TR and conductor 36 back to the negative polarity rail (rail 2 in the case of each of sections D—Da and Db—E and rail 1 in the case of section Da—Db).

Each time that the track relay TR picks up, contact 11 thereof completes for the local winding 30 of relay CTR an exciting circuit which may be traced from terminal B of the 100 cycle alternating current source through front contact 11, conductor 38 and the winding 30 back to terminal C of the alternating current source. In consequence, both of the windings 29 and 30 of the auxiliary relay CTR are simultaneously energized from source B—C during each pulse of the coded signal control energy which is received from the trackway. During, however, the intervals ("off" code periods) which separate these received pulses, both of the windings 29 and 30 are simultaneously deenergized; the supply circuit for winding 29 then being interrupted by the coding contact 80 or 180 of device CT at the exit end of the signal block and the circuit for winding 30 being interrupted at contact 11 during each released condition of the code following track relay TR.

As long as the polarity of the energization of winding 29 is of the "normal" character originally selected for the associated track circuit, the code step recurring pulses of energy which are applied to the windings 29 and 30 produce a normal direction rotation of the fly ball mechanism 31 which is sufficiently high in speed to bring the contacts of relay CTR into their picked-up positions and there maintain them as long as coded energy continues to be received from the track circuit. The bridging of the "off" code periods is readily effected by the high rotative inertia of the fly ball mechanism 31 which, in conventional designs of the centrifugal track relays, is sufficient to keep the rotor spinning freely for about two seconds after energy is removed from the windings 29 and 30 before the front contacts of the relay open and for about two additional seconds after this time of opening until the back contacts of the relay are closed.

Contact 33 of relay CTR is thus maintained picked up as long as relay TR at the same location continues to follow a signal control code during normal operation of the system and under these conditions it connects the heel of the pole changing contact 12 with the positive terminal of the exciting source for the decoding transformer DT over a circuit which extends from that positive terminal through front contact 33 and conductor 39. As has already been pointed out, this enables the code following track relay to cause the decoding relays DRH and DR180 to control the wayside signal S in the normal automatic block system manner which has already been explained in detail.

The disclosed arrangement of the auxiliary track relays CTR further is such that these relays in no way interfere with the response of the signaling equipment to the entry of a train into

and passage through the track sections of the signaled stretch. Under such conditions, the code following track relay TR is deenergized in the usual manner by the shunting action of the wheels and axles and both of the decoding relays DRH and DR180 are released in the same manner as were the auxiliary relays CTR not to form a part of the signal location equipment. Under occupied conditions of the section, moreover, both of the windings 29 and 30 of this added device CTR are deenergized so that it releases its contacts. As the train leaves the section, the restoration of the coded energy to relay TR causes it to follow code in the usual manner and to relay CTR causes this device quickly to bring the fly ball mechanism 31 up to normal speed and thereby pick up contact 33 and reconnect the pole changing circuit for the decoding transformer DT with the positive terminal of the exciting source.

In considering the manner in which the just described facilities prevent the giving of a false "proceed" signal indication in the event of a broken-down rail joint, assume that while passing over the joints 3 at location D of Fig. 1a a train causes either or both of them to break down and establish a path over which energy from the rails of the rear track section may feed into the rails of the forward section. This rear section energy is, as has been seen, of a polarity which is opposite to that of the forward section energy; accordingly, at the instant when rail 1 of the rear section is negative rail 1 of the forward section normally is positive and at the instant when rail 2 of the rear section is positive rail 2 of the forward section normally is negative.

Because of the presence of the train in the rear portion of the section D—Da, relay TR at location D is at first continuously deenergized, as is also the auxiliary relay CTR and, in consequence, the contacts of both of the decoding relays DRH and DR180 are dropped out in the normal manner to cause the controlled wayside signal Sd to display the "stop" or red indication which is appropriate for the occupied condition of the signal block of which location D marks the entrance. Under this condition, the rails of the section to the rear of location D are supplied with energy of the 80 coding over a circuit previously traced as including back contact 24 of relay DRH.

As soon as the rear of the before mentioned train has passed far enough beyond the signal location D to allow an "on" period of the 80 code energy (feeding from the rear to the forward section over the defective joint and the impedance bond return path) to energize the track relay TR, the front contacts of this relay become picked up and contact 11 completes the exciting circuit over which the local winding 30 of relay CTR receives normal polarity excitation. In the meantime, winding 29 of that relay is receiving the reversed polarity leakage energy from the rear track section. The path over which this leakage energy flows may be traced from the right terminal of transformer TT at location D through rail 2 of the rear track section, the defective rail joint 3, rail 2 of the forward section, conductor 36, the winding 29 of relay CTR, conductor 34, rail 1 of the forward section, the second defective joint 3 (or the impedance bond return path), rail 1 of the rear section and impedance 8 back to the left terminal of the track transformer TT.

It will be noted that whereas normal polarity energy from track section D—Da causes current

75

to circulate through winding 29 in the direction of from left to right, the reversed polarity leakage energy from the rear track section causes current to circulate through this winding in the 5 opposite direction, or from right to left. Meanwhile, the polarity of the excitation of the local winding 30 of relay CTR remains the same as before and for this reason the rotor mechanism of the relay is urged to rotate in the reversed 10 direction. Because, however, of the before described ratchet device (not shown) which permits the fly balls to be rotated only in the normal or forward direction, no movement of the mechanism 31 is possible and the contacts of the 15 relay accordingly cannot be picked up by the rear section energy which leaks over the defective rail joints.

In remaining in its released position, contact 33 of relay CTR disconnects the exciting circuit 20 of the decoding transformer DT from the direct current source. Even though, now, the signaling system track relay TR follows the coding of the rear section leakage energy, it is ineffective for picking up either of relays DRH and DR180 25 and, as a result, the wayside signal Sd continues to display the red or "stop" indication by virtue of the lighting circuit for lamp R continuing to be completed over back contact 18 of relay DRH. This "stop" indication by the signal at 30 the location of the defective joint continues uninterruptedly as the train advances entirely out of the track block D—E, and thus guards the section against an unsafe entry by a following train.

35. When the rear of the departing train clears the exit end location E, coded signal control energy from that location once more is transmitted over the rails to the entrance end D. Here it may be so interfered with by the leakage energy from the rear track section that relay TR cannot respond thereto in normal manner and in that event the "stop" aspect of the wayside signal Sd will continue until the broken-down joint is repaired. In the event, however, 40 that the relays TR and CTR are able to respond to the forward section energy, the controlled signal Sd will display an indication which is no more permissive than had the insulated joints 45 3 at location D not failed. The train being out 50 of the block D—E, no increased hazards to safety are thereby introduced by the faulty joint.

From a comparison of the equipment which is represented at location E of Fig. 1b with that 55 which has just been described for location D of Fig. 1a, it will be seen that the broken-down joint protection facilities are the same in both instances. The protection facilities shown at location E are, in fact, all that will be required 60 to practice our invention when the signal block contains no cut sections and the rails thereof are electrically continuous from the entrance to the exit end. In such installations no line wires are needed between the signal locations to effect 65 the broken-down joint protection, for by coding the local winding 30 of the protective relay CTR over a front contact 11 of the code following track relay TR the centrifugal device CTR is prevented from being damped during the "off" 70 code intervals in the same effective manner as were its energizing circuit to be carried over a line wire to the exit end of the track circuit and there connected in parallel with the track transformer TT, as has been customary in the past.

75. It will be seen, moreover, that the scheme is

applicable to coded signaling systems of types other than the "frequency code" arrangement which has been disclosed by way of illustration and that the invention is not restricted to any particular form of decoding apparatus and circuits. It is, in fact, applicable to coded systems of all types which employ track relays of the single element code following type, such as have been represented at TR in the present drawings. The details of equipment now typified by relays DRH and DR180 are, therefore, unimportant as long as they permit the protective relays CTR to discontinue the usual track relay control thereof when the protective relay becomes released in response to the reversed polarity energy which is received over a faulty rail joint from the rear track section.

Regarding the manner in which the control winding 29 of the protective relay CTR is connected with the track rails, it has already been 20 pointed out that the serial inclusion of this winding in the supply circuit for the code following track relay TR is only one of a number of different ways by which this winding may receive a measure of the trackway energy which is applied to the code following device TR. It is, of course, true that the represented serial connection of the two track relays tends to limit the length of the track circuit to, say approximately 4500 to 5000 feet as compared with around 6000 25 feet when the code following relay TR is used alone, yet this reduction in operable track circuit length is so comparatively small as not to be greatly objectionable. Besides, the stated limitation may readily be overcome by the use of 30 cut sections of any one of a number of well-known code repeating types.

In certain cases it may be desirable to substitute for the previously discussed serial connection of the two relays TR and CTR a parallel 40 connection of their control windings of the general character which is represented in Fig. 4. Here the conductors 34 and 36 leading from the track rails 1 and 2 join respectively with conductors 37 and 35 between which the control winding of each of the two relays TR and CTR is connected. As in the case of the serial connection, normal polarity energy received from the associated track section causes current to flow through winding 29 in the direction of from left 45 to right, while reversed polarity energy from the rear track section which leaks over a defective rail joint 3 causes current to flow through the winding 29 in the opposite direction, or from right to left. The former causes the relay CTR 50 to pick up its contacts, while the latter is ineffective for this purpose and thereby provides the protection against the defective rail joint in precisely the same manner as does the before described serial connection.

It has also been pointed out that the protective relay TR need not in all instances be of the illustrated centrifugal frequency selective type. It may, for example, be of the slow release polarized type which is represented at CTRa in Fig. 5. 65 There the local or exciting winding 30 is constantly energized from the alternating current source B—C, while the control or track winding 29 is connected to receive energy from the rails 1 and 2.

A relay of the type shown in Fig. 5 has no rotating element and obtains its slowness of contact release by means of a dash pot or other well-known expedients. The magnitude of this release delay must, as has been indicated previ- 70 75

ously, be sufficient to span the maximum spacing which occurs between recurrent or consecutive pulses of the coded signal control energy which is received from the trackway during normal operation of the signaling system, and to which the code following device TR is called upon to respond.

When current having an instantaneous relative polarity of the so-called "normal" variety is circulating through the control (rail-connected) winding of the protective relay CTR^a of Fig. 5, the contacts of the relay are moved to their illustrated picked-up positions. When, however, the control winding receives current of reverse polarity, the interaction with the local winding 30 is reversed and the contacts then are forced downwardly into their released positions. In this manner, it will be seen that the modified form of relay shown at CTR^a in Fig. 5 is capable of effecting protection against the broken-down rail joints in precisely the same manner as is the previously described centrifugal type of relay shown at CTR in the earlier figures.

A further advantage of the herein disclosed scheme of our invention is that it is capable of extending the broken-down joint protection to all highway crossing signals which are within the limits of each of the main signal blocks of the automatic wayside system. In the case of the single main block D—E of the composite diagram of Fig. 1a—b, such a highway crossing signal is shown at XS in association with each of the two cut locations Da and Db which respectively are occasioned by the two intersecting highways 6 and 7.

Each of these crossing signals XS is controlled by an operation governing relay XR which when energized holds a contact 42 picked up and thereby maintains the signal inactive. When, however, this contact 42 is released, it completes for the signal XS an operating circuit which may be traced from the positive terminal of a suitable supply source through back contact 42, a conductor 43, the operating mechanism (not shown in detail) of the crossing signal XS and back to the negative terminal of the supply source.

Normally, relay XR receives energizing current over a circuit which is controlled by the equipment which is installed at the entrance end of the track section over which railway traffic normally approaches the intersection that the signal XS guards. In the case of both of the crossing signals which are represented, this control relay circuit extends from the positive terminal of a suitable supply source through a front contact 44 of the broken-down joint protective relay CTR, conductor 45, a front contact 46 of a slow release relay FP, a line conductor 47 and the winding of relay XR back to the negative terminal of the supply source.

The just mentioned device FP is a front contact repeater for the track relay TR and is provided with an energizing circuit which includes a front contact 13 of that code following device. Each time that this contact picks up in response to a pulse of trackway energy being received by relay TR, the winding of relay FP is energized over a circuit which may be traced from the positive terminal of a suitable supply source through front contact 13, conductor 49 and the winding of relay FP back to the negative terminal of the supply source.

As already indicated, relay FP is a slow releasing device and the magnitude of its release delay is sufficiently long that it keeps its contacts con-

tinuously picked up between adjacent pulses of trackway energy which the code following relay TR receives during normal operation of the signaling system. This delay is preferably provided through the use of a snubbing resistor 50 bridged across the relay winding and serving to sustain the flux in the magnetic circuit of the relay for an appreciable period following each interruption of winding energizing current.

As long as the track relay TR follows either of the two codes which the transmitter CT at the exit end of the signal block produces, relay FP is held continuously picked up and its contact 46 connects conductor 45 with conductor 47. Under the same conditions, the protective relay CTR 15 also is picked up and its contact 44 completes the energizing circuit for control relay XR at cut location Da and thereby maintains the associated highway crossing signal XS inactive. The conditions just described are, of course, in effect as long as the approach section D—Da remains unoccupied during normal operation of the signaling system. The same is true of the crossing signal XS which is installed at the second cut location Db.

As will be evident from an inspection of the composite diagram of Figs. 1a—b, the relays FP and CTR which govern the control relay for this second signal XS at location Db are installed at the entrance end Da of the track section over which normal direction railway traffic approaches the second intersecting highway 7. Additionally installed at this entrance location Da (first cut) are facilities for repeating into the rails of the track section to the rear thereof each pulse of coded energy which is received from the rails of the adjoining forward section together with still further means for supplying steady energy to the rear section when there is received from the forward section either no energy at all or steady energy.

The former facilities include a code following track relay TR which receives operating current from the forward section rails and a track transformer TT which supplies the rear section rails with energy from source B—C each time that relay TR is picked up. The latter facilities further include front contact repeater relay FP and a second or back contact repeater BP for the track relay TR.

Devices TR, CTR and FP at both of the two cut locations Da and Db are related to the track circuits and to each other in precisely the same manner as has already been described in connection with location D. That is, the control windings of relays TR and CTR are serially connected between the rails 1 and 2 of the track section which extends forwardly from their locations; the local winding 30 of relay CTR is supplied from alternating current source B—C with exciting current over a circuit which includes conductor 38 and which is completed each time that contact 11 of relay TR is picked up; and the slow release relay FP receives energization over a direct current circuit which includes conductor 49 and which is completed each time that contact 13 of relay TR is picked up.

Regarding the back contact repeater relay BP, its energizing circuit is completed each time that contact 13 of relay TR releases provided a contact 52 of relay FP is at the time picked up. Under such conditions, the circuit may be traced from the positive supply terminal through back contact 13, conductor 53, front contact 52 of re-

lay FP, conductor 54 and the winding of relay BP back to the negative supply terminal.

Like relay FP, the second repeater relay BP is sufficiently slow releasing that it keeps its contacts continuously picked up between adjacent pulses of trackway energy to which the track relay TR responds during normal operation of the signaling system. Preferably, this release delay is provided through the use of a snubbing resistor 55 bridged across the relay winding. In order that this resistor will be effective only when a companion relay FP is picked up, the snubbing circuit in which it is included is carried over contact 52 of relay FP. This assures that each release of relay FP will be followed almost immediately by a release of relay BP, the delayed release characteristics of the latter relay being effective only when relay FP is picked up.

In operation of the energy repeating facilities shown at cut section location Da, relay TR follows the coding of the energy which is received from the forward track section and thus causes both of the repeater relays FP and BP to remain picked up as long as this code following operation takes place. Each time now that relay TR picks up in response to a pulse of forward circuit energy, the rails to the rear of location Da receive a pulse of trackway energy from the transformer TT; this results from contact 11 of relay TR completing for the primary of transformer TT an energizing circuit which extends from terminal B of the alternating current source through front contact 11, conductors 57 and 26 and the primary of transformer TT back to terminal C of the alternating current source. Likewise each time that relay TR releases its contacts this supply of energy to the rear circuit is discontinued. In this manner the trackway code is repeated around the insulated joints 3 which define the first cut Da in the main signal block.

In the case, however, that no energy is received from the forward section, the apparatus at location Da then supplies steady energy to the rails of the rear section over a circuit which is completed by a back contact 58 of relay BP and which may be traced from terminal B through back contact 68, conductor 26 and the primary of transformer TT back to supply terminal C. This results from track relay TR being continuously released and allowing repeater relays FP and BP also to release.

At the second cut location Db in the main signal block D—E, the energy repeating apparatus is arranged in a slightly different manner than at the first location Da. The back contact repeater relay BP is dispensed with and the supply circuit for the track transformer TT is completed over the back point of contact 11 of the code following track relay TR. This arrangement is known as "back contact coding" and it so operates that each "off" period of the code which is received from the forward section rails produces an "on" period in the code repeated into the rear section rails by virtue of contact 11 of relay TR completing for transformer TT an energizing circuit which may be traced from supply terminal B through back contact 7, conductor 26 and the primary of transformer TT back to supply terminal C. Moreover, this same circuit assures that an absence of energy in the entrance end of the forward track circuit will cause the steady energy to be supplied to the rails of the rear track section.

The manner in which the highway crossing signals XS at the two cut locations Da and Db

are controlled and protected against the giving of false "clear" indications due to broken-down rail joints will now be considered. As long as the main signal block D—E remains vacant both of these signals are maintained inactive. In the case of device XS at the first cut location Da this inactivity results from relays CTR and FP at location D being held picked up by the coded energy which is received at that location and completing the energizing circuit for the crossing signal control relay XR. In the case of device XS at the second cut location Db the named inactivity similarly results from relays CTR and FP at location Da being held picked up by coded energy which is received from the rails of section Da—Db.

In the event that a train traveling from left to right enters the section of which location D marks the entrance, the shunting action of its wheels and axles deenergizes relays TR, CTR and effects the release of relay FP at the location D. Relay FP releases relatively soon after the entry of the train and breaks at contact 46 the energizing circuit for relay XR which, in turn, completes the operating circuit for the crossing signal XS and brings this signal into operation thereby warning the users of highway 6 that a train is approaching. Later, contact 44 of relay CTR releases and additionally interrupts the supply circuit for relay XR.

As the front of the train passes the first cut location Da and enters the next succeeding track section in advance, the shunting action now effective in the rails of that section deenergizes relays TR and CTR at location Da and effects the release of repeater relays FP and BP at the same location. Contact 46 of relay FP causes relay XR at the second cut location Db to bring the highway crossing signal XS into action and warn the users of highway 7 that a train is approaching. At the same time contact 58 of relay BP connects transformer TT directly across the supply terminals B and C and thereby causes steady energy to be transmitted to the rails of the rear section D—Db.

As soon as the rear of the train clears location Da this steady energy is transmitted to the entrance end D of the rear section and there it holds relay TR continuously picked up which, in turn, causes relays FP and CTR also to pick up. Contacts 44 and 46 of these devices now complete for relay XR at location Da an energizing circuit which picks up contact 42 and thereby discontinues operation of the first highway crossing signal XS. Meanwhile, both of the decoding relays DRH and DRH 80 at location D remain released and thereby hold the controlled wayside signal Sd at "stop."

At location Db the second highway crossing signal XS continues in operation until the rear of the forwardly moving train has cleared location Db. At that time the rails of the central section Da—Db become effective for transmitting to the entrance end of that section the steady energy which they receive from the exit end transformer TT over the back point of constantly released contact 11 of track relay TR at location Db. This, in turn, holds relay TR at location Da continuously picked up and causes contacts 44 and 46 of relays CTR and FP at the same location to complete for relay XR at location Db an energizing circuit which picks up contact 42 of that relay and thereby discontinues operation of the second highway crossing signal XS.

Meanwhile, steady energy continues to be sup-

plied to the rails of the rear section D—Da as a result of contact 11 of relay TR at location Da connecting the track transformer TT at that location directly across the supply terminals B 5 and C. This causes the wayside signal Sd to continue its display of the "stop" or red indication. Such a display, moreover, persists under normal operating conditions of the signaling system until the rear of the train clears the exit end of the 10 main signal block D—E.

When that happens, the rails of section Db—E once more become effective for transmitting energy coded by contact 80 of device CT at the exit location rearwardly to the entrance location Db, 15 there that 80 coded energy is repeated around the insulated joints 3 and into the rails of the central section Da—Db by which it is transmitted to the entrance end Da. There it is again repeated around the joints 3 and into the rails of 20 the rear section D—Da. In being received at the entrance D of the main signal block, it acts upon code following track relay TR and causes decoding relay DRH only to pick up and thereby shifts the signal indication on the part of the wayside 25 signal Sd from "stop" to yellow or "approach." Meanwhile, both of the crossing signals XS at the two locations Da and Db continue inactive because of relays CTR and FP at each of the locations D and Da remaining picked up under the 30 influence of the coded energy.

In addition to preventing the controlled wayside signal Sd from displaying a false "proceed" indication in the event that one of the insulated joints 3 fails at location D, the protection facilities which we have illustrated at this location also are effective to safeguard the highway crossing signal XS at location Da from remaining inactive in the event of such a joint failure. The later protection comes about in the following manner.

40 The release of auxiliary track relay CTR which accompanies a leakage of reversed polarity energy over the defective joint from the rear section into the forward section rails interrupts at contact 44 the circuit for relay XR and thereby insures that 45 signal XS will continue in operation as long as any part of a train passing through section D—Da remains within that section. Without this protective precaution it will be seen that as soon as the rear of a train advances some distance beyond the entrance location D where a broken-down joint has developed, the response of the track relay TR to the rear section leakage energy would be effective to pick up the repeater relay FP and by completing at contact 46 the circuit 50 for relay XR discontinue operation of signal XS even though the train were still within the approach section D—Da.

By falsely indicating to the users of highway 6 that the intersection might safely be entered the 60 premature inactivity of signal XS just described would be highly hazardous in that it would lure highway users directly into the path of the approaching train. As has been seen, the protective expedients of our invention eliminate this 65 hazard and assure that the crossing signal XS will continue in operation for the required length of time even though a failure of the insulated rail joints 3 does occur at the entrance of the approach section.

70 Similar protection is provided for the second crossing signal XS at location Db. In this case the hazard guarded against is that which would be created should one of the joints 3 at location Da fail and thereby allow energy from the rear 75 section D—Da to leak forwardly into the rails of

the central section Da—Db. Under that condition, the auxiliary track relay CTR would release and thereby break at contact 44 the circuit for relay XR. This break, of course, makes it impossible for any subsequent picking up of contact 46 5 of relay FP to discontinue operation of the signal XS at location Db.

The protective expedients which we have just described may also be used in situations where the highway crossing signal is responsive to the approach of a train from either direction. Typically, such a two direction control scheme makes use of a double unit interlocked relay of the type represented at location Db as comprising devices XR1 and XR2.

Unit XR1 corresponds in all respects to relay XR already described in detail in connection with location Da, while the second unit XR2 may be of identical construction. Its winding is energized over a circuit which includes contacts 44a 20 and 48a of relays CTR and FP at the location of the crossing signal which is to be controlled. The two contacts 42 and 42a of the units XR1 and XR2 are so mechanically interlocked (by facilities not shown) that once either of the two contacts releases the other contact is prevented from releasing until the first is again picked up and also not until after the winding of the second relay unit has again been energized.

As long as the two sections of track which ad- 20 join at location Db remain vacant, the relays CTR and FP at both of the locations Da and Db are maintained picked up, both of the windings XR1 and XR2 of the interlocking relays are energized and the highway crossing signal XS is 25 maintained inactive by virtue of both of the contacts 42 and 42a being picked up. If a train moving in the forward direction of from left to right enters section Da—Db relays CTR and FP at location Da release and unit XR1 of the interlock- 30 ing relay drops contact 42 to bring the signal XS into operation at location Db.

As the train advances into section Db—E relays CTR and FP at location Db also release and deenergize the winding of interlocking relay unit 45 XR2. Contact 42a does not, however, release due to the action of the before described interlocking mechanism. Accordingly, when the rear of the train clears location Db, highway crossing signal XS ceases to operate as the result of contact 42 50 of relay XR1 being picked up. The original interlock of contact 42a persists until the winding of unit XR2 is again energized and this does not happen until the rear of the train clears the exit end E of the forward section.

If a train traveling in the reverse direction of from right to left enters the approach section Db—E, the crossing signal XS at location Db will again be brought into operation as a result of contact 42a releasing in response to the deenergization of winding XR2 which is effected by the release of contacts 44a and 46a of relays CTR and FP at location Db. This release, of course, accompanies the deenergization of the track relay TR which is produced by the rail shunting action of the train wheels and axles. As the train advances into section Db—Da, it similarly effects a release of relays CTR and FP at location Da and an accompanying deenergization of winding XR1 of the interlocking relay. Contact 42, how- 65 ever, does not now release due to the before mentioned interlocking action.

When the rear of the reverse moving train 70 clears location Db, operation of the signal XS once more ceases as the result of contact 42a be- 75

ing picked up in response to the energization of relays CTR and FP at location Da. The original interlock of contact 42 continues until the rear of the departing train clears location Da.

- 5 From the foregoing it will be seen that in the case of the forwardly moving train the signal XS at intersection Db is protected from premature inaction upon failure of a rail joint 3 at location Da in the same manner as that already described 10 in connection with the crossing control system using the single unit governing relay XR. Likewise, it will be seen that in the case of the reverse moving train the same crossing signal XS at intersection Db is similarly protected in the event 15 that one of the rail joints 3 at location Db should fail while a train is within the section Db—E.

In the latter situation the tendency would be 20 for the energy from section Da—Db to leak over the faulty joint and operate relay TR in such manner as to keep the signal XS at intersection Db inactive until the reverse running train had approached very close to the intersection. With the scheme which we have represented, however, relay CTR at location Db does not respond to the 25 leakage energy and thus it opens at contact 44a the energizing circuit for interlocking unit XR2 as soon as the train enters section Db—E and in this manner the desired control of the crossing signals is at all times assured.

- 30 Referring now to Fig. 3, we have there represented one manner in which our improved circuits may be arranged in case it is desired to provide the crossing signal XS at intersection Da with a two direction control scheme of the type 35 just described in connection with the crossing signal at intersection Db.

It will be noted from Fig. 3 that unit XR1 of 40 the interlocking relay replaces the single unit relay XR now shown in Fig. 1a, and that the unit XR2 is connected in a manner which is identical with the connections of the corresponding unit now shown at location Db in Fig. 1b. In addition to the contacts 44 and 45 which control the crossing signal at the advance cut location Db, the 45 relays CTR and FP at location Da are provided with the contacts Da and 46a which are arranged in the manner shown.

In view of the complete description of the two 50 direction running system which has already been given, it is thought that the manner of operation of the extended circuits of Fig. 3 will be fully apparent.

Reverting to certain more general features of the broken-down rail joint defective scheme of 55 our invention, the use of the centrifugal frequency selective type of relay which is represented at CTR is especially desirable in applications that employ direct current track relays TR which receive pick-up energy through resonant 60 rectifier units of the character represented at 9 in Fig. 1 and shown in greater detail in Fig. 2. Should, for any reason, this unit fail to keep out of the 25 cycle per second propulsion energy, the code following track relay TR will, of course, be 65 energized continuously. In so far as the wayside signals S are concerned, such failure would not introduce any hazard to safety for the reason that the failure of the track relay TR to follow code will cause the controlled wayside signal to 70 go to "stop" and there continuously remain.

In the case of the highway crossing signals XS, however, a failure of the type described in the preceding paragraph would, in the absence of the special protective relays CTR herein disclosed, 75 pick up repeated relay FP and thereby maintain

the crossing signal XS at the cut section in advance inactive even though a train might be in the section of track which interconnects the wayside signal location (such as D in Fig. 1a) with the cut section (such as Da in Fig. 1a) where the 5 crossing signal XS is positioned. It will be noted, however, that the centrifugal frequency selective relay CTR effectively prevents this hazardous possibility due to the fact that it is unable to respond to the low or 25 cycle propulsion energy 10 which may reach the control winding 29 thereof. Such failure to respond is due to the fact that the local winding 30 is excited by 100 cycle per second energy and to the further fact that even were this exciting winding also to receive 25 cycle 15 energy the speed of rotation of the fly ball mechanism 31 which would result still would be far too low to raise the contacts 33 and 44 to their picked-up positions. Contact 44 thus remaining open, the crossing signal XS would be continued 20 in action.

In all of the applications which we have disclosed herein, moreover, should the insulated rail joints break down when the affected sections 25 of track are vacant, the polarity selective characteristics of the protective relay CTR will in each instance cause that relay to release when winding 29 thereof receives the reverse polarity energy which leaks over the faulty joints from the rear track section into the track section 30 ahead. In the case of the wayside signals S, as has been seen, contact 33 now assures the "stop" 35 indication by rendering inactive the decoding apparatus (relays DRH and DR180), while in the case of the highway crossing signals XS contact 44 assures that a warning will be continued as long as needed. The functions just 40 named cannot, of course, be performed by a single element track relay of the type shown at TR for the reason that such a relay is not selective 45 as to polarity. To make it such, moreover, and yet retain its code following characteristics would greatly complicate its design, substantially add to its cost, and minimize the reliability of its operation. Hence, the special utility of the 50 scheme which we have herein disclosed as utilizing a supplemental protective relay CTR.

From the foregoing it will be seen that we have provided new and improved forms of organization of railway traffic controlling apparatus into signaling systems wherein coded energy 55 normally is supplied to the track circuits for the purpose of controlling either or both wayside signals and train carried cab signals and in which code following track relays of the single element 60 type are utilized. All of these organizations are effective to detect the failure of the insulated joints which electrically separate the rails of adjacent track sections and in the event of such failure to prevent the controlled wayside signals from giving false "proceed" indications, and to 65 continue highway crossing signals in operation as long as a warning therefrom is needed to advise highway users of an approaching train. This protection is effected without the necessity 70 for line wires interconnecting the opposite ends of automatic signal blocks and it may readily be extended to all highway crossing signals which are within the limits of each of those blocks. All of the above, moreover, has been accomplished 75 without dispensing with any of the desirable features of continuously coded track circuits.

Although we have herein shown and described only a few of the many possible forms of railway 75

traffic controlling apparatus embodying our invention, it is understood that various changes and modifications may be made therein within the scope of the appended claims without departing from the spirit and scope of our invention.

Having thus described our invention, what we claim is:

1. In combination with adjoining forward and rear sections of railway track which are electrically separated by insulated rail joints, means for supplying the rails of said forward section with periodically interrupted energy of a given polarity, a code following track relay connected to receive operating energy from said rails, a signal so controlled by said track relay as to give a non-restrictive aspect when the track relay is responding to said periodically interrupted energy and a danger aspect when the track relay is continuously released, means for supplying the rails of said rear section with energy having a polarity which is opposite to that of said forward section energy, a slow-release auxiliary relay connected in energy receiving relation with said forward section rails and arranged to pick up only in response to received energy which has said given polarity and to release should opposite polarity energy or no energy at all be received, and means governed by said auxiliary relay for causing said signal also to give said danger aspect whenever the auxiliary relay is released whereby to assure that said signal will provide a warning indication in the event that said insulated rail joints should break down and transmit said opposite polarity energy from the rear track section into the forward track section.
  2. In combination with adjoining forward and rear sections of railway track which are electrically separated by insulated rail joints, means for supplying periodically interrupted energy of a given polarity to the rails of said forward section, a code following track relay connected to receive operating energy from said rails, a signal so controlled by said track relay as to give a non-restrictive aspect when the track relay is responding to said periodically interrupted energy and a danger aspect when the track relay is continuously released, means for supplying the rails of said rear section with periodically interrupted energy having a polarity which is opposite to that of said forward section energy, an auxiliary relay connected to receive energy from said forward section rails and arranged to pick up when said received energy has said given polarity and there continuously stays even though that energy is periodically interrupted and to release should opposite polarity energy or no energy at all be received, and means governed by said auxiliary relay for causing said signal also to give said danger aspect whenever the auxiliary relay is released whereby to assure that said signal will provide a warning indication in the event that said opposite polarity energy should feed over said insulated rail joints from the rear track section into the forward track section.
  3. In combination with adjoining forward and rear sections of railway track which are electrically separated by insulated rail joints, means for supplying periodically interrupted energy of a given polarity to the rails of said forward section, a code following track relay connected to receive operating energy from said rails, a signal so controlled by said track relay as to give a non-restrictive aspect when the track relay is responding to said periodically interrupted energy and a danger aspect when the track relay is continuously released, means for supplying the rails of said rear section with periodically interrupted energy having a polarity which is opposite to that of said forward section energy,
- responding to said periodically interrupted energy and a danger aspect when the track relay is continuously released, means for supplying the rails of said rear section with periodically interrupted energy having a polarity which is opposite to that of said forward section energy, an auxiliary relay of the centrifugal type provided with a control winding connected in energy receiving relation with said forward section rails and also having an exciting winding, means controlled by said track relay for impressing given polarity energy upon said exciting winding each time that the track relay is energized whereby to cause said auxiliary relay to pick up and there stay continuously when said periodically interrupted energy of said given polarity is received by said control winding from the forward section rails and to release should opposite polarity energy or no energy at all be received, and means governed by said auxiliary relay for also causing said signal to display said danger aspect whenever the auxiliary relay is released whereby to assure that that signal will give a warning indication in the event that said opposite polarity energy should feed over said insulated rail joints from the rear track section into the forward track section.
4. In combination with adjoining forward and rear sections of railway track which are electrically separated by insulated rail joints, means for supplying periodically interrupted energy of a given polarity to the rails of said forward section, a code following track relay, a supply circuit connecting the winding of said track relay across said forward section rails whereby that relay receives operating energy from those rails, a signal so controlled by said track relay as to give a non-restrictive aspect when the track relay is responding to said periodically interrupted energy and a danger aspect when the track relay is continuously released, means for supplying the rails of said rear section with periodically interrupted energy having a polarity which is opposite to that of said forward section energy, an auxiliary relay having a control winding which is serially included in said track relay supply circuit and which also receives energy from said forward section rails, said auxiliary relay being arranged to pick up when said received energy is of said given polarity and there continuously stay even though that energy is periodically interrupted and to release should opposite polarity energy or no energy at all be received, and means governed by said auxiliary relay for causing said signal also to display said danger aspect whenever the auxiliary relay releases as in response to opposite polarity energy leaking over said insulated rail joints.
5. In combination with adjoining forward and rear sections of railway track which are electrically separated by insulated rail joints, means for supplying periodically interrupted energy of a given polarity to the rails of said forward section, a code following track relay, a supply circuit connecting the winding of said track relay across said forward section rails whereby that relay receives operating energy from those rails, a signal so controlled by said track relay as to give a non-restrictive aspect when the track relay is responding to said periodically interrupted energy and a danger aspect when the track relay is continuously released, means for supplying the rails of said rear section with periodically interrupted energy having a polarity which is opposite to that of said forward section energy,

- an auxiliary relay of the centrifugal type provided with a control winding which is serially included in said track relay supply circuit and also having an exciting winding, means controlled by said track relay for impressing given polarity energy upon said exciting winding each time that the track relay is energized whereby to cause said auxiliary relay to pick up and there stay continuously when said periodically interrupted energy of said given polarity is received by said control winding from the forward section rails and to release should opposite polarity energy or no energy at all be received, and means governed by said auxiliary relay for also causing said signal to display said danger aspect whenever the auxiliary relay is released as in response to opposite polarity energy leaking over said insulated rail joints.
6. In combination with adjoining forward and rear sections of railway track which are electrically separated by insulated rail joints, means for supplying periodically interrupted energy of a given polarity to the rails of said forward section, a code following track relay, a supply circuit connecting the winding of said track relay across said forward section rails whereby that relay receives operating energy from those rails, a signal so controlled by said track relay as to give a non-restrictive aspect when the track relay is responding to said periodically interrupted energy and a danger aspect when the track relay is continuously released, means for supplying the rails of said rear section with periodically interrupted energy having a polarity which is opposite to that of said forward section energy, an auxiliary relay having a control winding which is connected in parallel with said track relay winding whereby also to receive energy from said forward section rails, said auxiliary relay being arranged to pick up when said received energy is of said given polarity and there continuously stay even though that energy is periodically interrupted and to release should opposite polarity energy or no energy at all be received, and means governed by said auxiliary relay for also causing said signal to display said danger aspect whenever the auxiliary relay is released as in response to opposite polarity energy leaking over said rail joints.
7. In combination with adjoining forward and rear sections of railway track which are electrically separated by insulated rail joints, means for supplying the rails of said forward section with periodically interrupted energy of a given polarity, a code following track relay connected to receive operating energy from said rails, a way-side signal positioned at the entrance of said forward section and so controlled by said track relay as to give a permissive aspect when the track relay is responding to said periodically interrupted energy and a "stop" aspect when the track relay continuously occupies either the picked up or the released position, means for supplying the rails of said rear section with periodically interrupted energy having a polarity which is opposite to that of said forward section energy, an auxiliary relay connected to receive energy from said forward section rails and arranged to pick up when said received energy has said given polarity and there continuously stay even though that energy is periodically interrupted and to release should opposite polarity energy or no energy at all be received, and means governed by said auxiliary relay for causing said signal also to show "stop" whenever the aux-

iliary relay is released whereby to assure that that signal will give a warning indication in the event that said opposite polarity energy should feed over said insulated rail joints from the rear track section into the forward track section. 5

8. In combination with adjoining forward and rear sections of railway track, means for supplying the rails of said forward section with periodically interrupted energy of a given polarity, a code following track relay operated by energy received from said rails, a decoding transformer, a source of unidirectional exciting current therefor, an exciting circuit by way of which said transformer is connected with said source over a contact of said track relay, a signal positioned 15 at the entrance of said forward section and so controlled by the output energy of said decoding transformer as to give a permissive indication when said track relay is responding to said periodically interrupted energy and to show "stop" 20 either when that relay fails to follow code or when the decoding transformer is continuously disconnected from its said exciting source, means for supplying the rails of said rear section with periodically interrupted energy of a polarity 25 which is opposite to that of said forward section energy, an auxiliary relay connected to receive energy from said forward section rails and arranged to pick up when said energy has said given polarity and there continuously stay even 30 though that energy is periodically interrupted and to release should opposite polarity energy or no energy at all be received, and means governed by said auxiliary relay for disconnecting said transformer from said exciting source whenever the auxiliary relay is released whereby to cause said signal also to give said "stop" indication in the event that said opposite polarity energy should leak from the rear track section 35 into the forward track section. 40

9. In combination with adjoining forward and rear sections of railway track, means for supplying the rails of said forward section with periodically interrupted energy of a given polarity, a code following track relay operated by energy received from said rails, decoding means including a transformer and a source of exciting current connected with the transformer over a pole changing contact of said track relay, a signal positioned at the entrance of said forward 50 section and so controlled by said decoding means as to give a permissive indication when said track relay pole changes the exciting current for said transformer and to show "stop" when the track relay fails to follow code or when the transformer 55 is disconnected from said exciting source, means for supplying the rails of said rear section with energy having a polarity which is opposite to that of said forward section energy, a slow release auxiliary relay receiving energy from said 60 forward section rails and arranged to pick up when that received energy is of said given polarity and to release should opposite polarity energy or no energy at all be received, and means governed by said auxiliary relay for disconnecting said transformer from said exciting source 65 whenever the auxiliary relay is released whereby to cause said signal also to give said "stop" indication in the event that said opposite polarity energy should leak from the rear track section 70 into the forward track section. 75

10. In combination with adjoining forward and rear sections of railway track, means for supplying the rails of said forward section with periodically interrupted energy of a given polar- 75

- ity, a code following track relay operated by energy received from said rails, a decoding transformer, a source of unidirectional exciting current therefor, an exciting circuit by way of which said transformer is connected with said source over a contact of said track relay, a signal positioned at the entrance of said forward section and so controlled by the output energy of said decoding transformer as to give a permissive indication when said track relay is responding to said periodically interrupted energy and to show "stop" either when that relay fails to follow code or when the decoding transformer is continuously disconnected from its said exciting source, means for supplying the rails of said rear section with periodically interrupted energy of a polarity which is opposite to that of said forward section energy, a slow release auxiliary relay receiving energy from said forward section rails and arranged to pick up when that received energy is of said given polarity and to release should opposite polarity energy or no energy at all be received, and a front contact of said auxiliary relay included in the said exciting circuit of said decoding transformer for the purpose of continuously disconnecting that transformer from its said exciting source should energy of said opposite polarity be transmitted into the forward section rails.
11. In combination with adjoining forward and rear sections of railway track which are electrically separated by insulated rail joints, means for supplying the rails of said forward section with energy which has a given polarity and which is periodically interrupted under certain conditions and steady under others, a code following track relay connected to receive operating energy from said rails, a highway crossing signal at the exit end of said forward section, means governed by said track relay for maintaining said crossing signal inactive when the track relay either is responding to said periodically interrupted energy or is continuously picked up and for placing that signal in operation when the track relay is continuously released, means for supplying the rails of said rear section with periodically interrupted energy having a polarity which is opposite to that of said forward section energy, a slow release auxiliary relay connected in energy receiving relation with said forward section rails and arranged to pick up only in response to received energy which has said given polarity and to release should opposite polarity energy or no energy at all be received, and means governed by said auxiliary relay for also placing said crossing signal in operation whenever the auxiliary relay is released, means for supplying the rails of said rear section with periodically interrupted energy having a polarity which is opposite to that of said forward section energy, a slow release auxiliary relay receiving energy from said rear section rails and arranged to pick up when that received energy is of said given polarity and to release should opposite polarity energy or no energy at all be received, and means including a contact of said auxiliary relay for also placing said crossing signal in operation whenever the auxiliary relay is released.
12. In combination with adjoining forward and rear sections of railway track which are electrically separated by insulated rail joints, means for supplying the rails of said forward section with energy which has a given polarity and which is periodically interrupted under certain conditions and steady under others, a code following track relay connected to receive operating energy from said rails, a highway crossing signal at the exit end of said forward section, means governed by said track relay for maintaining said crossing signal inactive when the track relay either is responding to said periodically interrupted energy or is continuously picked up and for placing that signal in operation when the track relay is continuously released, a relay for controlling the operation of said signal arranged to maintain the signal inactive when picked up and to place the signal in operation when released, an energizing circuit for said signal control relay which includes a front contact of said repeater relay whereby said signal comes into operation when the repeater relay is released, means for supplying the rails of said rear section with periodically interrupted energy having a polarity which is opposite to that of said forward section energy.
13. In combination with adjoining forward and rear sections of railway track, means for supplying the rails of said forward section with energy which has a given polarity and which is periodically interrupted under certain conditions and steady under others, a code following track relay connected to receive operating energy from said rails, a slow release repeater relay energized over a front contact of said track relay and arranged to pick up when the track relay either is responding to said periodically interrupted energy or is continuously picked up and to release when the track relay is continuously released, a highway crossing signal controlled by said repeater relay and arranged to be maintained inactive when the repeater relay is picked up and to be placed in operation when the repeater relay is released, means for supplying the rails of said rear section with periodically interrupted energy having a polarity which is opposite to that of said forward section energy, an auxiliary relay also connected to receive energy from said forward section rails and arranged to pick up when said received energy is of said given polarity and in either said periodically interrupted or said steady form and to release should opposite polarity energy or no energy at all be received, and means governed by said auxiliary relay for also placing said crossing signal in operation whenever the auxiliary relay is released whereby to assure that a warning indication will be given by that signal in the event that said opposite polarity energy should feed over said insulated rail joints from the rear track section into the forward track section.
14. In combination with adjoining forward and rear sections of railway track, means for supplying the rails of said forward section with energy having a given polarity and which is periodically interrupted under certain conditions and steady under others, a code following track relay connected to receive operating energy from said rails, a slow release repeater relay energized over a front contact of said track relay and arranged to pick up when the track relay either is responding to said periodically interrupted energy or is continuously picked up and to release when the track relay is continuously released, a highway crossing signal, a relay for controlling the operation of said signal arranged to maintain the signal inactive when picked up and to place the signal in operation when released, an energizing circuit for said signal control relay which includes a front contact of said repeater relay whereby said signal comes into operation when the repeater relay is released, means for supplying the rails of said rear section with periodically interrupted energy having a polarity which is opposite to that of said forward section energy.

an auxiliary relay also connected to receive energy from said forward section rails and arranged to pick up when said received energy is of said given polarity and in either said periodically interrupted or said steady form and to release should opposite polarity energy or no energy at all be received, and a front contact of said auxiliary relay serially included in the said energizing circuit for said signal control relay whereby to cause said signal also to be brought into operation whenever the auxiliary relay is released.

15. In combination with adjoining forward and rear sections of railway track, means for supplying the rails of said forward section with energy which has a given polarity and which is periodically interrupted under certain conditions and steady under others, a code following track relay operated by energy received from said rails, a first slow release relay energized when said track relay is picked up, a second slow release relay energized when said track relay is released provided said first slow release relay is picked up, a source of energy for the rails of said rear track section having a polarity which is opposite to that of said forward section energy, a circuit controlled by said track relay for connecting said source to said rear section rails each time that the track relay is picked up whereby periodically interrupted energy received from the forward section rails will cause periodically interrupted energy of opposite polarity to be supplied to those rear section rails, another circuit controlled by said second slow release relay for also connecting said source to said rear section rails whenever the second slow release relay is released whereby either steady energy or no energy at all received from the forward section rails will cause steady energy of opposite polarity to be supplied to those rear section rails, a highway crossing signal controlled by said first slow release relay and arranged to be maintained inactive when the first slow release relay is picked up and to be placed in operation when that relay is released, an auxiliary relay also connected to receive energy from said forward section rails and arranged to pick up when said received energy is of said given polarity and in either said periodically interrupted or said steady form and to release should

opposite polarity energy or no energy at all be received, and means governed by said auxiliary relay for also placing said crossing signal in operation whenever the auxiliary relay is released whereby to assure that that signal will provide a warning indication in the event that said opposite polarity energy should leak from the rear track section into the forward track section.

16. In combination with consecutive rear, central and forward sections of railway track, means for supplying the rails of said forward section with periodically interrupted energy of a given polarity, means at the junction of said central and forward sections for supplying the rails of said central section with opposite polarity energy which is periodically interrupted when periodically interrupted energy is received from said forward section rails and which is steady when no energy is received from those forward rails, means at the junction of said rear and central sections including a code following track relay connected with said central section rails for supplying the rails of said rear section with given polarity energy which is periodically interrupted when periodically interrupted energy is received by the relay from said central section rails and which is steady both when steady energy and when no energy at all is received, a highway crossing signal at the exit of said central section so governed by said track relay as to be maintained inactive when that relay is responding to periodically interrupted energy and to be placed in operation when the track relay is continuously released, a slow release auxiliary relay connected in energy receiving relation with said central section rails and arranged to pick up only in response to received energy which has said opposite polarity and to release should given polarity energy or no energy at all be received, and means governed by said auxiliary relay for also placing said crossing signal in operation whenever the auxiliary relay is released whereby to assure that that signal will provide a warning indication in the event that said given polarity energy should leak from the rear track section into the central track section.
